UNITED STATES PATENT OFFICE.

DAVID KENNEDY, OF LONDON, ENGLAND.

PERCUSSION-FUSE.

1,321,455.

Specification of Letters Patent.

Patented Nov. 11, 1919.

Application filed February 3, 1919. Serial No. 274,761.

To all whom it may concern:

Be it known that I, DAVID KENNEDY, a subject of the King of England, residing at London, England, have invented certain 5 new and useful Improvements in Percussion-Fuses, of which the following is a specification.

This invention relates to percussion or impact fuses for projectiles (which term includes such devices as bombs and hand-grenades) of the kind which are intended to detonate a charge irrespective of the direction of impact. The invention is particularly applicable to the so-called "all-ways" 15 fuse of a Stokes shell.

A primary object of the invention is to provide an improved fuse of the type which comprises a casing, a sliding striker therein held away from a detonator by a spring, 20 and a tumbler having a stem which projects through a cap on the casing, is a loose fit therein, and has a head which is situated on that end which lies within the cap and bears against the striker, the construction and arrangement of the fuse being such that the 25 fuse will operate reliably irrespective of the direction in which impact may occur.

Another object is to obviate miss-fires due to wear of that part of the casing which acts 30 as an abutment for the head of the tumbler when lateral impact occurs.

It has heretofore been proposed to construct a fuse of this type, wherein the head of the tumbler was concave on that side 35 which bore against the striker, and the striker was convex; the head, moreover, had its shoulder, which bore against the inner side of the cap, sunk in a recess which fitted the head. This known construction and arrangement falls outside the scope of this 40 invention.

A fuse according to the present invention preferably has the convex head so mounted that its sides cannot touch the sides of the 45 chamber containing it; for example, the shouldered portion of the head may be recessed and engage an upstanding rim on the cap of the casing.

To these ends, the invention consists in 50 the construction, arrangement and combination of parts described hereinafter and pointed out in the claims.

One embodiment of the invention and a

modification thereof is represented by way of example in the accompanying drawing, 55 wherein:

Figure 1 is a longitudinal sectional elevation showing one form of fuse according to the invention,

Fig. 2 is a top plan view thereof after the 60 domed cover-plate has been removed, and

Fig. 3 is a detail view of the tumbler;

Fig. 4 is a vertical section showing a modified form of striker according to the 65 invention.

Referring to Figs. 1 to 3, a cylindrical casing A is provided with means such as an internally and externally screw-threaded adapter A¹ for securing it to the shell or other explosive missile with which it is to 70 be employed. A detonator-carrier B is free to slide in the casing A and rests on the adapter A¹. A striker C is slidably mounted in the casing A and carries the usual striker point C¹. It is kept away from the 75 detonator-carrier and the detonator-carrier from it by one or more flat springs D. These parts are all the same as those which have heretofore been employed in the "all-ways" fuse, except that the face C² of the 80 striker which is adjacent to a tumbler E described hereinafter is made flat instead of its being in the form of a conical recess similar to that shown at F¹ in Fig. 4 such as is used in the "all-ways" fuse in which 85 a ball is used instead of a tumbler, which ball, as is well-known, operates between the striker and an oppositely-recessed cap.

The tumbler E has a stem E¹ which extends through a central orifice G¹ in a cap G which is screwed into the end of the cylindrical casing A, and the head E² of the tumbler has a convex face E³ which bears against the flat face C² of the striker C. The shoulder of the head E² which bears 95 against the cap G is recessed at E⁴ and the cap G is provided with an upstanding rim or flange G² which enters this recess. The orifice G¹ in the cap is considerably larger than the stem E¹, so that the latter is a 100 loose fit in the cap and consequently can rock therein, but it is kept in a central position by the flange G² and the sides of the head E² are thus kept clear of the inner sides of the casing A.

To prevent the tumbler E from being

driven inward accidentally it may be inclosed by a domed cover-plate H carried by the cap G.

The operation of this percussion fuse is 5 as follows:—

Lateral impact causes the stem E¹, which is heavy, to be thrown to one side or the other so that the tumbler E is rocked on the cap G about the edge of its shouldered 10 head E², with the result that the convex face E³ operates as a cam against the striker C and forces it toward the detonator-carrier, so that the pin C¹ detonates the pellet. If the impact acts end-on to the 15 tumbler in the one direction the whole tumbler of course moves bodily axially toward the detonator-carrier, while if the impact acts endwise in the opposite direction, the detonator is jerked against the point of the 20 striker owing to the momentum of its carrier.

It has been found that if the shoulder of the head E² is made to fit the chamber A, or is received in a recess in the cap G for 25 the purpose of centering the tumbler, its edge digs into the metal surrounding it when lateral impact occurs, with the result that the tumbler is not always thrown over and consequently the fuse is at times inoperative. It will be seen that the central 30 flange G² on the cap, while centering the tumbler, allows no possibility of this defective operation.

Instead of the above-described striker C 35 the striker F shown in Fig. 4, the body of which is already in use in the "all-ways" fuse, may be employed, the striker-pin used therewith being, however, removed and substituted by a striker-pin F¹ having a large 40 head F² within the conical recess F⁰. The known striker-pin used heretofore does not project into the recess F⁰ and this recess would prevent the convex face of the tumbler from operating the striker satisfactorily, whereas if a pin F¹ having a large 45 head F² is inserted, or any projection F² is secured in the recess F⁰ of the said known striker-body, this head or projection serves as an abutment for the head E², and thus 50 the striker used heretofore can be modified to be used with the improved form of tumbler described above.

What I claim as my invention and desire to secure by Letters Patent is:—

55 1. In a percussion fuse of the character described, the combination with a casing, a detonator-carrier supported therein at one end thereof, a cap having a central orifice mounted in the other end of the casing, a 60 striker slidable in the casing between the cap and the detonator-carrier, and a spring between the striker and the detonator-carrier, of a tumbler having a stem which extends

with play through said orifice and has on its inner end a head which has a convex face 65 bearing against the striker, said cap having annular guiding means thereon to center the head and prevent it from touching the casing, for the purpose specified.

2. In a percussion fuse of the character 70 described, the combination with a casing, a detonator-carrier supported therein at one end thereof, a cap having a central orifice mounted on the other end of the casing, a striker slidable in the casing between the cap 75 and the detonator-carrier, and a spring between the striker and the detonator-carrier, of a tumbler having a stem which extends with play through said orifice and has on its inner end a head which has a convex 80 face bearing against the striker, said head having an annular recess surrounding the stem, and said cap having an annular rim which normally takes into said recess and centers the head, for the purpose specified. 85

3. In a percussion fuse of the character described, the combination of a casing, a detonator-carrier supported therein at one end thereof, a cap having a central orifice mounted on the other end of the casing, a striker 90 slidable in the casing between the cap and the detonator-carrier and having a flat-bottomed recess in its face remote from the detonator-carrier, a spring compressed between the striker and the detonator-carrier, 95 and a tumbler having a stem which extends with play through the said orifice and has on its inner end a head which has a convex face bearing against the flat bottom of the 100 said recess in the striker, for the purpose specified.

4. In a percussion fuse of the character described, the combination of a casing, a detonator 105 therein, a striker therefor, a cap for said casing having a central orifice, a projecting rim surrounding said orifice, and a tumbler having a stem extending with play through said orifice, said tumbler having an annular recess adapted to receive 110 said projecting rim to hold the tumbler out of contact with the casing, substantially as described.

5. A percussion fuse having a detonator-carrier supported at one end of a casing, a cap having a central orifice at the other end 115 of the casing, a striker slidable between said cap and detonator carrier and a tumbler having a stem which extends with play through the said orifice, characterized by the tumbler being formed with an annular recess surrounding the stem and by the cap having an annular rim which normally projects within said recess for the purpose specified, substantially as described. 120

In testimony whereof I affix my signature. 125
DAVID KENNEDY.
